TRUNK PISTON

William F. Peterson, Kirkwood, Mo., assignor, by mesne assignments, to Sterling Aluminum Products, Inc., St. Louis, Mo., a corporation of Missouri

Application September 16, 1950, Serial No. 185,261

8 Claims. (Cl. 309—13)

This invention pertains to trunk pistons such as are used in internal combustion engines and in particular to such pistons constructed of light metals, such as aluminum and magnesium and their alloys, which are of relatively high thermal expansion. The method of making the trunk piston is claimed in application Serial No. 553,083, filed December 14, 1955.

A trunk piston of the type described comprises a head, a skirt, and wrist pin bosses on the inside of the skirt. The head is grooved to receive the piston rings and is of smaller diameter than the skirt, which provides the guiding cross-head for the piston. The skirt is separated from the head in one or both regions of the thrust faces by circumferential slots. The skirt may be of circular contour but is usually made oval with the major diameter in the regions of the thrust faces and with the minor diameter in the regions of the bosses. Some pistons have vertical slots.

The action of such a piston in an internal combustion engine is as follows: When heat is applied to the head, such heat is transmitted to the skirt in the regions of the bosses because of separation of the skirt from the head in the region or regions of a thrust face or faces. That causes the skirt to expand along the wrist pin boss axis where the outside of the skirt is relieved, resulting in drawing in of the skirt along the thrust axis. Such an action has been well-known for years. Where, however, the piston is of a metal such as aluminum, magnesium, and their alloys, of high thermal expansion, difficulty is experienced in having the piston fit closely to the cylinder walls at different times without seizing or slapping; therefore, resort was had to struts and other control elements of a metal of low thermal expansion such as steel.

One of the objects is to provide a light metal piston of novel structure, having a control element of a lower coefficient of expansion than the skirt applied in such a manner as to control expansion of the skirt diameter.

Other objects will be apparent to those skilled in the art in the light of the following specification and accompanying drawing.

Referring now to the drawings:

Figure 1 is a view in side elevation partly cut away, showing one embodiment of this invention;

Figure 2 is a sectional view taken along the line 2—2 of Figure 1;

Figure 3 is a bottom plan view;

Figure 4 is a sectional view taken along the line 4—4 of Figure 1; and

Figure 5 is a perspective view of a U-shaped insert for use with this invention.

Referring now to the accompanying drawing, 1 designates the skirt and 2 the head of a piston of the character described; that is, one of a metal such as aluminum or magnesium or their alloys of high thermal expansion. The skirt is provided with thrust faces 3, and with wrist pin bosses 4, connected to the head by strengthening ribs 40, and the head is provided with the usual piston packing grooves 14. The skirt may be circumferentially sep-

2

arated from the head in one or both regions of the thrust faces by a slot or slots 11, and one of these thrust faces may be provided with a vertical slot 12 extending downwardly from such separation. The skirt is thus attached to the head in the regions of the bosses, but separated from the head in one or both regions of the thrust faces.

The control element as shown in Fig. 5 is made of a metal of low thermal expansion such as steel. In the particular embodiment described, the control element 5 comprises a circumferential part 5, and side parts 6, which latter may be straight or of curved shape and which may extend inwardly at their ends.

Referring first to the top of the skirt, a control element 5, 6, is positioned at the top of and inside of the skirt with its side parts rigidly anchored against movement in the regions of the bosses and specifically in the vertical strengthening ribs 40, and with its connecting circumferential part extending circumferentially along and against a separated thrust face. The ends of the side parts may also bear against the thrust face opposite to that of the circumferential part, by the provision of bosses 10. The inside face of the circumferential part of the control element is exposed and is simply supported against shifting by ribs 15 and 16. The rib 15, may be of a shallow dimension radially, as shown in Figs. 2 and 4, and may extend not only along the circumferential part of the control element, but also along the side parts thereof to the vertical ribs 40. Likewise, the rib 16, which as shown in Figs. 2 and 4 has a radial dimension to the inside edge of the control element, also extends along the exposed circumferential part and the side parts.

In making this piston the control element is placed in a mold, usually of the permanent type, in which the piston is cast, and on a suitable permanent core, which in pistons of this type comprises a three-piece center core and two side cores, the later containing recesses, forming the wrist pin bosses 4, while the mold may be provided with cores to form the holes in the bosses. The outer pieces of the center core as well as the side cores are slotted as usual to receive the control element. At this time, of course, all circumferential and vertical slotting such as the slots 11 and 12, are absent as are also the piston ring grooves. After the piston has been cast in the manner described and has solidified the cores are withdrawn as usual in molding practice by permanent molds and the mold is opened.

Solidification of the casting will cause the piston metal to shrink and contract faster than the control element. This will result in the side parts of the control element to be rigidly cast-anchored against movement in the regions of the bosses by shrinking thereon of the piston metal and the bosses 10 will also shrink on the side parts of the control element. This will place the circumferential part of the control element under compression radially with the piston metal along that circumferential part placed under tension by shrinking of the piston metal on that connecting circumferential part. When, now the skirt is separated from the head by the formation of the slots 11 above the circumferential part of the control element, the above-described compression and tension will be somewhat relieved and any gripping axially of the ribs 15 and 16 on the control element will also, upon cooling of the piston, have been relieved.

The piston is now finished by cutting the packing ring grooves 14, by machining the head to the proper diameter and by machining the skirt to the desired contour, which as stated above is usually one in which the piston will be oval, with the minor axis along the wrist pin axis and the major axis along the thrust face axis. The piston can, however, be ground round.

A piston of the character described and made as described can be made with a very low clearance and it

will still maintain a close fit in the cylinder when either hot or cold. As the piston heats up, the head will, of course, expand radially in all directions. Such radial expansion of the head will however, only be transmitted to the skirt in the regions of the bosses. That will tend to move the skirt in along the line of the thrust faces. Such movement is permitted because the steel control element is pushed along the wrist pin axis and will pull the steel in along the thrust face axis and that will be followed by the piston metal (aluminum) outside of the circumferential part 5. The side parts 6, are however rigidly anchored in the thrust faces because the metal is cast entirely therearound. The piston metal does not however surround the circumferential part 5, but only lies against the outside thereof and, in the particular embodiment shown, against the side thereof. The control element having its inner portion exposed circumferentially and axially, said control element at said thrust face and the metal thereover is therefore under radial stress when the piston is cold, which stress is progressively relieved as the piston heats up in the engine so as to maintain the skirt dimension diametrically. The skirt at the thrust faces will therefore remain accurately dimensioned by the control element.

If desired, the thrust face opposite that at which the circumferential part of the control element is positioned, may also be separated from the head by a circumferential slot 11, and may be provided with a vertical slot 12. That renders the piston somewhat more flexible.

In the embodiment shown in Figs. 1 and 2, there is a second control element positioned at the bottom of and inside of the skirt, anchored in the regions of the bosses and extending circumferentially along and against the separated thrust face. Such a control element, like that shown in Fig. 5, is shown as anchored between ribs 41 and 42, in the regions of the bosses with the side parts also anchored in bosses 10 and with the circumferential part 5 between ribs 41 and 42 similar to the ribs 15 and 16. In fact, the rib 42 may be omitted as shown in Fig. 3. Such a control element at the bottom of the skirt may be used with a control element at the top of the skirt. It is formed in the same way in the casting of the piston in a permanent mold on a permanent core.

It will therefore be seen that the invention accomplishes its objectives. A piston is provided which can be closely fitted to a cylinder of an internal combustion engine and which will maintain its dimensions from hot to cold so that there will be no seizing when hot and no slapping when cold.

Having thus described the invention, what is claimed is:

1. A trunk piston of a metal of relatively high thermal expansion, comprising, a head, a skirt provided with wrist pin bosses and with thrust faces, one of said thrust faces being circumferentially separated from said head, and a control element of a metal of low thermal expansion positioned at the top of and inside of said skirt, said control element having side parts rigidly anchored against movement in the regions of the bosses and having a connecting part extending circumferentially along and against said separated thrust face having its inner portion exposed circumferentially and axially, said control element at said thrust face and the metal thereover being under radial stress when the piston is cold, which stress is progressively relieved as the piston heats up in the engine, adapted to maintain the skirt dimension diametrically.

2. A trunk piston of a metal of relatively high thermal expansion, comprising, a head, a skirt provided with wrist pin bosses and with thrust faces, one of said thrust faces being circumferentially separated from said head, and a control element of a metal of low thermal expansion positioned at the top of and inside of said skirt and over which element the skirt is cast, said control element having side parts rigidly cast-anchored against movement in the regions of the bosses by shrinking thereon of the

skirt metal and having a connecting part extending circumferentially along and against said separated thrust face but having its inner portion exposed circumferentially and axially, said control element at said thrust face and the metal thereover being under radial stress when the piston is cold, which stress is progressively relieved as the piston heats up in the engine, adapted to maintain the skirt dimension diametrically.

3. A trunk piston of a metal of relatively high thermal expansion, comprising, a head, a skirt provided with wrist pin bosses and with thrust faces, one of said thrust faces being circumferentially separated from said head, and a control element of a metal of low thermal expansion positioned at the top of and inside of said skirt and over which element the skirt is cast, said control element having side parts rigidly cast-anchored against movement in the regions of the bosses by shrinking thereon of the skirt metal and having a connecting part extending circumferentially along and against which bears said separated thrust face by shrinking of the skirt metal radially inwardly on said connecting part, said connecting part having its inner portion exposed circumferentially and axially, said control element at said thrust face and the metal thereover being under radial stress when the piston is cold, which stress is progressively relieved as the piston heats up in the engine, adapted to maintain the skirt dimension diametrically.

4. A trunk piston of a metal of relatively high thermal expansion, comprising, a head, a skirt provided with wrist pin bosses and with thrust faces, one of said thrust faces being circumferentially separated from said head, and a control element of a metal of low thermal expansion positioned at the top of and inside of said skirt, said control element having side parts rigidly anchored against movement in the regions of the bosses and in one thrust face, said control element having a connecting part extending circumferentially along and against the opposite separated thrust face having its inner portion exposed circumferentially and axially, said control element at said thrust face and the metal thereover being under radial stress when the piston is cold, which stress is progressively relieved as the piston heats up in the engine, adapted to maintain the skirt dimension diametrically.

5. A trunk piston of a metal of relatively high thermal expansion, comprising, a head, a skirt provided with wrist pin bosses and with thrust faces, one of said thrust faces being circumferentially separated from said head, and a control element of a metal of low thermal expansion positioned at the top of and inside of said skirt, said control element having side parts rigidly anchored against movement in the regions of the bosses and having a connecting part extending circumferentially along and against said separated thrust face, said connecting part bearing axially against a shoulder on the inside of said thrust face but having its inner portion exposed circumferentially and axially, said control element at said thrust face and the metal thereover being under radial stress when the piston is cold, which stress is progressively relieved as the piston heats up in the engine, adapted to maintain the skirt dimension diametrically.

6. A trunk piston of a metal of relatively high thermal expansion, comprising, a head, a skirt provided with wrist pin bosses and with thrust faces, one of said thrust faces being circumferentially separated from said head, and a control element of a metal of low thermal expansion positioned at the top of and inside of said skirt, said control element having side parts rigidly anchored against movement in the regions of the bosses and having a connecting part extending circumferentially along and against said separated thrust face, the other thrust face being also circumferentially separated from said head, said connecting part having its inner portion exposed circumferentially and axially, said control element at said thrust face and the metal thereover being under radial stress when the piston is cold, which stress is progressively re-

lied as the piston heats up in the engine, adapted to maintain the skirt dimension diametrically.

7. A trunk piston of a metal of relatively high thermal expansion, comprising, a head, a skirt provided with wrist pin bosses and with thrust faces, one of said thrust faces being circumferentially separated from said head, and a control element of a metal of low thermal expansion positioned at the top of and inside of said skirt, said control element having side parts rigidly anchored against movement in the regions of the bosses and having a connecting part extending circumferentially along and against said separated thrust face, the other thrust face being also circumferentially separated from said head and having a vertical slot extending downwardly from such separation, said connecting part having its inner portion exposed circumferentially and axially, said control element at said thrust face and the metal thereover being under radial stress when the piston is cold, which stress is progressively relieved as the piston heats up in the engine, adapted to maintain the skirt dimension diametrically.

8. A trunk piston of a metal of relatively high thermal expansion, comprising, a head, a skirt provided with wrist pin bosses and with thrust faces, one of said thrust faces being circumferentially separated from said head, and a control element of a metal of low thermal expansion positioned at the top of and inside of said skirt, said control element having side parts rigidly anchored against movement in the regions of the bosses and having a connecting part extending circumferentially along and against said

5
10

separated thrust face having its inner portion exposed circumferentially and axially, said control element at said thrust face and the metal thereover being under radial stress when the piston is cold, which stress is progressively relieved as the piston heats up in the engine, adapted to maintain the skirt dimension diametrically, and a second control element positioned at the bottom of and inside of said skirt, anchored in the regions of the bosses and extending circumferentially along and against said separated thrust face but having its inner portion exposed circumferentially and axially.
